Primary Examiner — Cathron C Brooks*Assistant Examiner* — Andrew T Nemeth*(74) Attorney, Agent, or Firm* — Cantor Colburn LLP(57) **CLAIM**

The ornamental design for a display screen or portion thereof with graphical user interface, as shown and described.

DESCRIPTION

FIG. 1 is a front view of a display screen or portion thereof with graphical user interface showing my new design in accordance with a first embodiment; and,

FIG. 2 is a front view of a display screen or portion thereof with graphical user interface showing my new design in accordance with a second embodiment.

The outermost broken lines illustrate a display screen or portion thereof and form no part of the claimed design. The remainder of the broken lines illustrate portions of the graphical user interface that form no part of the claimed design.
